US00D877971S

(12) **United States Design Patent** (10) Patent No.: **US D877,971 S**
(45) Date of Patent: **** Mar. 10, 2020**

(54) **VAPORIZER DEVICE WITH CARTRIDGE**

(71) Applicant: **Juul Labs, Inc.**, San Francisco, CA (US)

(72) Inventors: **Adam Bowen**, San Mateo, CA (US); **James Monsees**, San Francisco, CA (US); **Steven Christensen**, Burlingame, CA (US); **Christopher Nicholas HibmaCronan**, Oakland, CA (US); **Joshua Morenstein**, San Francisco, CA (US)

(73) Assignee: **JUUL Labs, Inc.**, San Francisco, CA (US)

(**) Term: **15 Years**

(21) Appl. No.: **29/542,362**

(22) Filed: **Oct. 13, 2015**

Related U.S. Application Data

(63) Continuation of application No. 29/499,018, filed on Aug. 11, 2014, now abandoned.
